Inventor
W.A.SHIELDS.

UNITED STATES PATENT OFFICE.

WILLIE A. SHIELDS, OF BIRMINGHAM, ALABAMA.

BAG-MOUNTING APPLIANCE.

Application filed April 23, 1924. Serial No. 708,328.

To all whom it may concern:

Be it known that I, WILLIE A. SHIELDS, a citizen of the United States of America, residing at Birmingham, in the county of Jefferson and State of Alabama, have invented certain new and useful Improvements in Bag-Mounting Appliances, of which the following is a specification.

My invention relates to a device for mounting paper bags on garments such as suits and dresses, where it is a problem to introduce the garment in a simple and easy manner, while mounted on the hanger, into a paper bag of the requisite length to protect it fully.

More particularly, my present invention is an improvement upon a device of this character patented to me on May 27th, 1919, No. 1,304,913, wherein I utilized a vertically movable bag mounting appliance. That required more head room than is always available at laundries and at cleaning and pressing plants and so I have found it necessary to devise an appliance capable of winding the bags on a rotatable spiral carrier with a mounting wire passing through the bag and having a hook at its free end for the suspension of a garment hanger. This would permit the bag to be drawn from its curved or spiral carrier and pulled down over the garment.

More particularly my invention contemplates a rotatable spiral guide for causing the bag mounting wire to easily wind itself through the paper bag so that the bag would not have a tendency to wrinkle or tear when being mounted on the appliance.

My invention also comprises a very simple and effective mechanism for operating the bag mounting appliance.

My invention in its preferred embodiment only is illustrated in the accompanying drawings which form a part of this specification, and in which:—

Fig. 1 is a perspective view of the appliance ready to have a bag wound thereon by the depression of the foot pedal and the rotation of the spiral mounting wire.

Fig. 2 shows my invention after operation with a bag in dotted lines wound on the mounting appliance ready to be drawn down over the garment suspended therefrom.

Fig. 3 is a cross-sectional view taken on the line 3—3 of Fig. 2.

Similar reference numerals refer to similar parts throughout the drawings.

My invention comprises a suitable bracket 1 adapted to be attached to a side wall or mounted in any other suitable manner, and having journaled therein a rotatable shaft 2, which is engaged by a coil spring 3 that tends to rock the shaft clockwise as viewed in Figs. 2 and 3. Fast on one end of the shaft is a pulley 4 having a notch 5 therein adapted to be engaged by a detent 6 on an arm 7 preferably pivoted to the bracket at 8, but it may be pivotally mounted on any suitable support. The free end of this arm 7 is inturned at 9 and perforated to receive a flexible cord or chain 10 which is wound about and made fast at one end to the pulley 4. At an intermediate point on the arm 7 I provide a connection 11 for a pull cord 12 leading to an operating foot pedal 13 having a hinge 14 to connect it to any suitable support, not shown. The cable 12 is so connected relative to the pivot points of the arm 7 and pedal 13 that a relatively short pedal movement will lower the arm sufficiently to give the pulley 4 and shaft 2 a complete rotation. It will be observed that the detent 6 will engage the notch 5 to limit the counter-clockwise spring actuated return of the shaft 2. When the lever is depressed its first action is to pull the detent out of the notch, there being sufficient play and slack in the cord 10 to permit this and then the pulley is rotated. By releasing the foot, the spring will return the parts to the initial position shown, permitting the detent 6 to again engage in the notch 5 and serve as a stop.

A typical paper bag 15, such as used by laundries, dry cleaners and the like for protecting garments, has a small center opening 16 at its top while its bottom is left open. I mount on the shaft 2 at the center a spiral mounting wire 17 having at its free end a hook 18 and fast on the shaft on each side of this wire 17 I mount a spiral guide wire 19. These wires are cross connected at their free ends by a leg 20 which stands slightly spaced below the wire 17, and the guide wires 19 being spaced far enough on each side of wire 17 to form effective guides for the support of the under part of the bag while it is being wound onto the mounting wire.

In operation, the paper bag 15 is grasped at its top on each side of the opening 16 and the hook end of the mounting wire 17 is caused to project into this opening. The 5 foot pedal is then depressed and as the mounting wire rotates the bag is held so that the wire coils itself through the bag until its hook end 18 projects through the open bottom of the bag. The guide wires 10 19 on each side hold the inner side of the bag, which is following the shorter radius, so that it will not buckle or wrinkle and keeps the bag flat and smooth as the mounting wire is wound through it. When the 15 hook end 18 of the mounting wire projects from the bag the garment 21, which is mounted on the usual garment hanger, is hung on the hook 18 and the open bottom end of the bag 15 at each side is grasped by 20 the operator and is drawn down, stripping it from the mounting wire and causing it to slip down over the garment until the garment hanger projects through the top opening 16 of the bag. For short bags a 25 single depression of the pedal may wind the bag sufficiently on the mounting wire to expose the hook 18 of the latter, but for full length dress bags it may be necessary to operate the pedal several times in order to get the full length of the bag wound on the 30 wire.

It is obvious that my present invention can be operated with very low head room, is compact, quite simple and inexpensive in 35 its structure, and is very readily mounted.

Though I have described with great particularity the details of the embodiment of the invention herein shown, it is not to be construed that I am limited thereto, as 40 changes in arrangement and substitution of equivalents may be made by those skilled in the art without departing from the invention as defined in the appended claims.

Having thus described my invention, what 45 I claim as new and desire to secure by Letters Patent, is:—

1. A bag mounter for garments, comprising a spiral mounting wire having a hook at its free end, and means to wind said wire

through a paper bag and expose its hook 50 to receive a garment hanger, substantially as described.

2. A bag mounter in accordance with claim 1, in combination with guide means for the inner side of the bag to prevent 55 wrinkling as it is wound on the mounting wire.

3. A bag mounter for garments, comprising a bracket, a shaft journaled in the bracket, a spiral mounting wire fast on the 60 shaft, a spiral guide mounted fast on the shaft between the latter and the mounting wire, and means to rotate said shaft.

4. A bag mounter for garments, comprising a bracket, a shaft journaled in the bracket, a spiral mounting wire fast on the shaft, spiral guide wires mounted on the shaft on each side of the mounting wire and disposed between the latter and the shaft, and means to rotate said shaft and wires comprising 70 a foot pedal connection and spring means to return the shaft to initial position.

5. A bag mounter comprising a bracket having a shaft journaled therein, spring means to rotate the shaft in one direction, a 75 pulley on the shaft, a pivoted arm having a flexible connection to the pulley to rotate the latter against the action of said spring, a foot pedal operating means for said pivot arm, a spiral mounting wire fast on the 80 shaft at its center, spiral guide wires fast on the shaft on each side of the mounting wire and cross connected at their free ends, a hook at the free end of the mounting wire, and stop means to limit the spring return 85 if the shaft.

6. A bag mounter according to claim 5, in which the stop means is formed by co-acting elements on the pulley and its operating arm.

7. A bag mounter in accordance with claim 5, in which the pulley operating arm is pivotally mounted in the shaft supporting bracket.

In testimony whereof I affix my signature.
WILLIE A. SHIELDS.
